UNITED STATES PATENT OFFICE.

TIMOTHY C. VAUGHN, OF MORRIS, MINNESOTA.

PNEUMATIC ELEVATOR.

Application filed June 22, 1921. Serial No. 479,550.

To all whom it may concern:

Be it known that I, TIMOTHY C. VAUGHN, a citizen of the United States, residing at Morris, in the county of Stevens and State 5 of Minnesota, have invented certain new and useful Improvements in Pneumatic Elevators; and I do hereby declare the following to be a full, clear, and exact description of the invention, such as will enable others 10 skilled in the art to which it appertains to make and use the same.

My present invention relates to improvements in pneumatic elevators for delivering grain into bins and the like, and has for its 15 object to provide an extremely simple and highly efficient structure, as will hereinafter appear.

To the above end, generally stated, the invention consists of the novel devices and 20 combinations of devices hereinafter described and defined in the claims.

In the accompanying drawings which illustrate the invention, like characters indicate like parts throughout the several views.

25 Referring to the drawings:-

Fig. 1 is a fragmentary plan view of the invention with some parts sectioned;

Fig. 2 is a view partly in side elevation and partly in central vertical section taken 30 on the line 2—2 of Fig. 1; and

Fig. 3 is a view in transverse vertical section taken on the line 3—3 of Fig. 1.

The numeral 4 indicates a cylindrical fan casing having, at its bottom, a tangential 35 horizontally disposed discharge throat 5, and the numeral 6 indicates a stack, the lower end of which is connected to said throat by an elbow 7. Within the fan casing 4, is a fan 8, the shaft 9 of which is mounted in adjustable bearings 10 carried by brackets 11 bolted to a pair of laterally spaced sills 12. On one end of the fan shaft 9 is a pulley 13 over which runs a belt, not shown, for driving the fan 8. The fan 8 is 40 driven in a direction to deliver a blast of air upward in the stack 6 through the throat 5 and elbow 7.

Co-operating with the blast of air in the stack 6 to deliver grain through said stack, 45 is a horizontally disposed paddle wheel comprising a cylindrical body or hub 15, having integral with its periphery, circumferentially spaced solid flanges 15^a to which are secured radially disposed solid blades 16. 50 These blades 16 overlap the flanges 15^a and are adjustably and detachably secured there-

to by nut-equipped bolts 16^a which extend through bores in the flanges 15^a and radially extended slots 16^b in said blades. The slots 16^b permit the blades 16 to be adjusted radially to vary the distance between their edges and a housing for the paddle wheel for a purpose that will presently appear. The overlapping of the blades 16 with the flanges 15^a forms tight joints therebetween. 55

The paddle wheel is mounted on a shaft 17 journaled in bearing heads 18 secured to the ends of a cylindrical housing 19 for said paddle wheel. This housing 19 is set into an opening in the top of the fan casing throat 70 5 and is provided with an opening 20 through which grain is delivered, by the paddle wheel, into the fan casing throat 5 and in the direction of the blast of air from the fan 8. The discharge opening 20 extends the full width of the housing 19 which has a width equal to the diameter of the stack 6 and the blades 16 extend through said housing with just sufficient space to clear the heads thereof. 75

The housing 19 is provided, diametrically opposite the discharge opening 20, with an extension 22 having a bottom 23 which inclines toward the bottom 21 of said housing. This extension 22 affords an intake 80 opening through which grain may be delivered under the action of gravity, on the inclined bottom 23 to the bottom 21 of the housing 19, where it will be caught or picked up by the blade 16 of the paddle wheel and 85 delivered through the opening 20 into the blast of air from the fan 8. It will be noted that the discharge opening 20 terminates below the top of the fan casing 5 to afford a deflecting flange 25. By reference to Fig. 2, 90 it will be noted, that certain of the blades 16 are always in position to extend diametrically through the casing 19 and thereby separate or form a partition between the discharge opening 20 and intake opening 24. 95

As previously stated, the blades 16 are solid and, as shown in Figs. 2 and 3, they extend from one end of the housing 19 to the other and to the periphery thereof, and thereby divide said housing into a plurality 100 of non-communicating compartments except between the outer longitudinal edges of the blades and the housing.

In the bottom of the housing 19 is a depression or pocket 19^a having, in its back, 110 an opening 19^b in the direct line of blast from the fan 8. This pocket 19^a is formed,

as shown, by extending the bottom 21, substantially, tangentially from the discharge opening 20 into underlapping arrangement with the bottom 21, rearward of the opening 19^b. The space between the sections of the bottom 21 is partly closed by a depending flange 19^c which terminates above the bottom of the pocket a distance sufficient to give the opening 19^b the desired height.

10 To deliver grain into the housing extension 22, there is provided a hopper 26 having an inclined bottom which terminates in a spout 27 which opens into one end of the housing extension 22. Grain may be discharged into the hopper 26 from a wagon box or other vehicle. The paddle wheel is driven in the same direction as the fan 8, therefrom, but at a slower speed, by means of a sprocket chain 28 which runs over a 15 relatively small sprocket wheel 29 on the fan shaft 9 and over a relatively large sprocket wheel 30 on the paddle shaft 17.

15 The operation of the improved pneumatic elevator may be briefly stated as follows:

20 25 Grain discharged into the hopper 26 slides down the bottom thereof and is fed through the contracted spout or neck 27 to the inclined bottom 23 of the housing extension and is carried therefrom, under the 20 action of gravity, onto the bottom 21 of the housing 19, where it is caught or picked up by the blades 16 of the paddle wheel and thrown, thereby, into the fan casing neck 5 and blast of air from the fan 8. The 25 capacity of the elevator may be governed, at will, by regulating the speed of the fan and the paddle wheel.

30 35 One purpose of the air vent 24 is to relieve the air pressure, produced by the paddle wheel when revolving at a very high speed, which would tend to hold back light grains and retard the movement thereof, to the blades 16 of the paddle wheel. A further purpose of the air vent 24 is to relieve back 40 pressure from the stack produced when elevating grain at a great height, which requires a very strong blast of air from the fan 8. If it were not for the air vent 24, this back pressure would produce a force in 45 the pockets of the paddle wheel formed by the blades 16 which would be carried thereby to the intake for the paddle wheel and onto the grain and thereby retard the movement thereof, and particularly of light 50 grains. By forming the air vent 24 between the discharge opening for the paddle wheel and the intake thereon, back pressure caught in the pockets of the paddle wheel, will be released through said vent before reaching 55 the intake for the grain.

60 65 To eliminate as much as possible any back pressure from entering the housing 19, after the blades 16 have passed the opening 20, it is highly desirable that said blades travel as close to the cylindrical surface of the

housing as possible, without danger of crushing grain or seeds on the bottom 21 of said housing by the blades 16. Owing to the different sizes of grains and seeds acted upon by the blades 16, said blades are 70 mounted for radial adjustment so that they may be set, to work at the best advantage. For instance, in elevating corn, the blades should be adjusted within, substantially, one-half an inch of the housing 19; in elevating wheat, the distance should be about one-quarter of an inch, and in elevating timothy or clover, the blades should be adjusted so that they just clear the housing. 75

80 To further assist in preventing back pressure in the housing 19, the pocket 19^a is provided, and which pocket is soon filled with grain or seeds after the paddle wheel is started, and as each blade 16 passes over the pocket, the grain is removed from the housing, only to the depth at which said blades penetrate, thus leaving the pocket 19^a filled with grain, which acts as a damper to prevent back pressure from entering between the blades 16 and housing bottom 21, and it also closes the opening 19^b. Before the pocket 19^a is filled with grain, or in case the same is emptied by the paddle wheel, a portion of the blast of air from the fan 8 will enter the housing 19 through the opening 19^b and thereby interrupt any back pressure entering the opening 20 and again direct the same toward the stack 6 where the same is caught by the blast from the fan and carried therewith. 95

100 The above described invention, while extremely simple and of comparatively small cost to manufacture, is thought to be highly efficient for the purpose had in view and has few parts that are liable to get out of order.

105 It is, of course, understood that the fan throat 5 and elbow 7 form sections of the stack 6, and, while said stack is shown perpendicular, it might, in some instances, be extended horizontally, obliquely, or in various other positions.

110 What I claim is:—

115 1. In a pneumatic elevator, the combination with a stack, of means for delivering a blast of air into the stack, a housing extending into the stack and contracting the same and having a discharge opening into the stack forward of the contracted portion thereof, means for delivering grain to the housing, paddle blades in the housing, and means for moving the paddle blades in a direction to deliver grain to said discharge, said housing having an air vent rearward of its discharge and exposed to the blast of air. 120

125 2. In a pneumatic elevator, the combination with a stack, of means for delivering a blast of air into the stack, a housing extending into the stack and contracting the same and having a discharge opening into the 130

stack forward of the contracted portion thereof, means for delivering grain to the housing, paddle blades in the housing, means for moving the paddle blades in a direction 5 to deliver grain to said discharge, and a deflecting flange extending into the stack at the top of the discharge.

3. In a pneumatic elevator, the combination with a stack, of means for delivering a 10 blast of air into the stack, a housing having an intake and a discharge, the latter of which opens into the stack, a pocket in the bottom of the housing between its intake and discharge, paddle blades in the housing separating 15 the same into non-communicating compartments except between the outer longitudinal edges of the paddle blades and the housing, means for moving the paddle blades in a direction to deliver grain to said discharge, said paddle blades being arranged so that when one thereof is in a position to release grain to the discharge, a following paddle blade is in a position between the intake and the pocket and still another of said paddle blades is in a position between said discharge and intake and moving toward said intake.

4. In a pneumatic elevator, the combination with a stack, of means for delivering a 20 blast of air into the stack, a housing having an intake and a discharge, the latter of which opens into the stack, paddle blades in the housing, and means for moving the paddle blades in a direction to deliver grain to the 25 discharge, the bottom of the housing, between the intake and discharge, being rearwardly and downwardly inclined and having an air vent exposed to the blast of air.

5. In a pneumatic elevator, the combination 30 with a stack, of means for delivering a blast of air through the stack, a paddle wheel housing having a discharge opening into the stack, means for delivering grain 35 into the stack forward of the contracted portion thereof, means for delivering grain to the housing, paddle blades in the housing, means for moving the paddle blades in a direction to deliver grain to said discharge, and a deflecting flange extending into the stack at the top of the discharge.

into said housing, a paddle wheel journaled in said housing means for driving the paddle wheel in a direction to deliver grain through said discharge opening and into the blast of air, and an air vent in said housing rearward of its discharge opening and exposed to the blast of air. 45

6. In a pneumatic elevator, the combination with a stack, of means for delivering a blast of air through the stack, a paddle wheel housing having in its bottom a pocket, and also having a discharge opening into the 50 stack forward of said pocket, means for delivering grain into said housing, a paddle wheel journaled in said housing and means for driving the paddle wheel in a direction to deliver grain through said discharge opening and into the blast of air. 55

7. In a pneumatic elevator, the combination with a stack, of means for delivering a blast of air through the stack, a paddle wheel housing having in its bottom a pocket, and also having a discharge opening into the 60 stack forward of said pocket, means for delivering grain into said housing, a paddle wheel journaled in said housing means for driving the paddle wheel in a direction to deliver grain through said discharge opening and into the blast of air. 65

8. In a pneumatic elevator, the combination with a stack, of a fan arranged to deliver a blast of air to the stack, a paddle wheel housing having a discharge opening into the stack, and also having in its bottom a pocket, said pocket having an air vent exposed to 70 said blast of air, a paddle wheel journaled in the housing and working over said pocket, and means for driving the paddle wheel in a direction to deliver grain into said blast of air. 75

In testimony whereof I affix my signature.
TIMOTHY C. VAUGHN.
